UNITED STATES PATENT OFFICE.

BERT E. BARTHOLOMEW, OF PASADENA, CALIFORNIA, ASSIGNOR, BY MESNE ASSIGNMENTS, TO BERT E. BARTHOLOMEW AND HERBERT PARKER.

CUPBOARD CATCH.

Application filed March 9, 1927. Serial No. 173,956.

This invention relates to catches for cupboards and the like, and it is an object of my invention to provide a catch that may be applied to a closet, cupboard, medicine-cabinet 5 or the like, and which catch is compact and has means for operating the same extending through the handle of the cupboard or medicine-chest door.

A still further object of my invention is to 10 provide a catch that may be readily disassembled and assembled within the recess in the door provided for it, and which has relatively few moving parts and consequently, is unlikely to get out of order.

15 A still further object of my invention is to provide a catch that is novel in its appearance, can be manufactured at a nominal sum, and is well adapted to perform the services required of it.

20 In the accompanying drawings forming a part of this specification, two figures have been deemed sufficient to clearly illustrate my invention, and

25 Figure 1 is a side view of my cupboard catch applied to a cupboard, showing a portion of the cupboard broken away to more clearly reveal the operative parts of my invention.

30 Figure 2 is a sectional view taken substantially along the lines 2—2 of Figure 1.

Referring to the accompanying drawings wherein similar reference characters designate similar parts throughout, a pair of cupboard doors are indicated at 1 and 2 respectively. 35 My cupboard catch is adapted to be received in a cut-away portion in one of these doors—in this case, the door 1. Toward this end the door is gouged for the reception of my improved cupboard catch, and in this gouged 40 portion of the door there is adapted to be inserted, my bolt assembly 3 and the releasing means assembly 4. These assemblies are separate and independent from each other but co-operate together when assembled to provide an entire cupboard catch assembly.

45 The actual bolt assembly comprises a casing 5, open at one end as at 6 and provided at the other end with a slot 7 through which a guiding shank 8 of a bolt 9 extends. This bolt 50 9 comprises a body portion beveled as at 10, and the body portion has on the upper surface of the same, a slot 11. The reduced shank 8 extends from one end of this bolt and is surrounded by a coil-spring 13 bearing 55 against shoulders 14 on the body portion,

and against the interior of the casing 5, in order that the bolt may at all times be urged to the position shown in Figure 2, partially extended from the casing. The releasing assembly comprises a substantially cylindrical 60 casing 15, through which diametrically extends the bolt assembly 3 as clearly shown at 17 in Figure 1. A second casing 18 is adapted to be received within the casing 15, and this second casing has a curved lower 65 portion indicated at 19, adapted to bear firmly against the casing 5. The casing 5 is provided with a diametrical slot 20 at the point where it contacts with the casing 18. A suitable pin 22 extends diametrically across 70 the casing 18, and pivoted on this pin 22 is a bell-crank link 23 having a cam surface 24 on one end thereof, and an arm 25 slightly curved as at 26, to extend through the slot 20 into the slot 11 in the bolt 9. This bell-crank 75 link is pivoted to the pin 22 and serves to operate the bolt 9 for the purpose of retracting the same. The casing 15 is exteriorly threaded throughout a portion of its length, and a knob 27 having a central bore there- 80 through and internal threads on a portion of said bore, is adapted to be received on the casing 15 in threaded engagement. This knob is provided with a flange 28 which bears firmly against the side of the cupboard when 85 the knob 27 is screwed on the casing 15. When the flange 28 does bear against the side of the cupboard, a considerable degree of tension is given to the casing 15 and the bolt assembly 3 is consequently held tightly in place. The 90 knob 27 is provided as at 30 with an internal, annular flange, and an adjustable button or finger-latch 31 is mounted for slidable movement within this flange. This finger-latch comprises a plug 32 and a socket member 33. 95 The socket member has an annular flange 34 formed thereon, which is adapted to have engagement with the internal, annular flange 30, to prevent the button from being removed from within the knob 27. The plug 32 is exteriorly threaded and has threaded engagement with the socket 33 which is internally threaded. The cupboard-door 2 is recessed as at 40, and a metal veneer plate 41 is inserted in the recess, into which plate the bolt 9 is 100 adapted to extend. The adjacent edges of the cupboard-doors are closely fitted together, and improper closing of these doors is provided for by means of the protruded portions 44 and 45 of the doors 2 and 1 respectively. 110

The door 2 may be provided with a blind knob 46 if desired.

I will now describe in detail the exact operation of my device, which includes the operation of assembling and dissembling the same and the actual operation of the elements employed in carrying out my invention. The releasing means assembly is first inserted in the cupboard door, and the bolt assembly 3 is inserted through the portion 17 so that the releasing means assembly can not be pulled from its respective recess. The adjustable finger-latch 31 is inserted in the knob 27, the cylindrical casing 18 is inserted in the casing 15, and the handle is screwed on the last mentioned casing with the finger-latch therein until the flange 28 bears against the cupboard, thereby holding all parts in operative relation against removal. Depression of the finger-latch 31 causes the plug 22 to bear against the cam surface 24 on the short arm of the bell-crank link 23, and the arm 25 is caused to swing, carrying with it the bolt 9 against the compression of the coil-spring 13. When the pressure on the finger-latch 31 is relieved, the bolt is instantly projected from its respective casing. To dissemble the device it is merely necessary to reverse this operation and all of the operative parts may be removed.

I do not desire to limit myself particularly to the use of my invention on cupboards, cabinets and the like, but may apply the principles of the same to any manner of swinging door, casement or the like. I further contemplate the use of my invention in connection with sliding doors, casements and the like, and if desired, my improved latch might well be employed to latch a chest of drawers, a window, sliding door, and in fact, my invention can be applied universally as a catch.

It will be understood that various changes in the detail of construction may be made without departing from the spirit or scope of the invention as defined by the appended claims.

I claim:

1. The combination with a door, of an open-ended casing within said door, a bolt slideable within said casing, means for normally urging said bolt from said casing, a second casing through which said first casing extends, an internal sleeve in said casing, a single bell-crank link pivoted in said sleeve, one arm of which engages said bolt and is

adapted upon movement to move the same, 55 the other arm providing a cam surface, a hollow knob threadedly receivable by said second mentioned casing, a finger-latch extending from said knob, adapted to engage said cam surface to operate said bell-crank link 60 and said bolt.

2. The combination with a door, of an open-ended casing within said door, a bolt slideable within said casing, means for normally urging said bolt from said casing, a second casing through which said first casing extends, 65 an internal sleeve in said casing, a single bell-crank link pivoted in said sleeve, one arm of which engages said bolt and is adapted upon movement to move the same, the other 70 arm providing a cam surface, a hollow knob threadedly receivable by said second mentioned casing, an adjustable finger-latch comprising a plug and socket member threaded- 75 ly receivable one within the other.

3. The combination with a door of an open ended casing within said door, a bolt slideable within said casing, a spring for normally urging said bolt from said casing, a second casing through which said first casing extends, 80 and a single bell crank link pivoted therein, one arm of which engages said bolt and is adapted upon movement to move the same against the tension of said spring, the other arm providing a cam surface, and a finger 85 latch adapted to engage said cam surface to operate said bell crank link and said bolt.

4. The combination with a door of an open ended casing within said door, a bolt slideable within said casing, means for normally urging said bolt from said casing, a second casing through which said first casing extends, 90 an internal sleeve in said casing, a single crank link pivoted in said sleeve, one arm of which engages said bolt and is adapted upon 95 movement to move the same, the other arm providing a cam surface, a hollow knob threadedly receivable by said second mentioned casing, a finger latch extending from 100 said knob, said finger latch having a flange limiting its movement outwardly from the knob, and an adjustable plug screw threaded on said latch and adapted to engage said cam surface to operate said bell crank link and said bolt.

In testimony whereof I have signed my name to this specification.

BERT E. BARTHOLOMEW.
